UNITED STATES PATENT OFFICE.

JEROME P. COSTELLO, OF PUEBLO, COLORADO.

BREAKABLE RAIL ANCHOR.

Application filed March 15, 1927. Serial No. 175,563.

This invention relates to rail anchors and has for an object the provision of an anchor which is of great strength in gripping a rail and in resisting the creeping tendency 5 thereof, but which is so formed as to have but a minimum of strength in those parts which are normally subjected to no stress or strain.

Another object is to provide a rail anchor, 10 of the class referred to, which will break under the impact of a derailed car wheel and thereby obviate the breaking out of pieces along the edge of a rail base when a derailed car wheel strikes the anchors.

15 These and other objects are attained by the means described herein and disclosed in the accompanying drawings, in which:

Fig. 1 is a front elevational view of an embodiment of this invention, operatively 20 mounted upon a rail and abutting a railroad tie.

Fig. 2 is a view taken on line 2—2 of Fig. 1.

In the present embodiment of the invention, there is provided a two-piece rail anchor comprising a shoe 5, which may be of cast iron or other suitable metal. The shoe 5 has a bottom flange 6 adapted to abut the bottom face 7 of the flange 8 of a rail 9. The body of the shoe 5 extends about the longitudinal edge 10 of the rail flange and is substantially C-shaped in the front elevation (see Fig. 1). A top flange 11 of the shoe 5 overhangs the bottom flange 6 for a distance, thereby providing a way 12 for receiving the longitudinal flange 8 of a rail 9. The body of the shoe 5 and overhanging flange 11 tapers from its end 14 which abuts the tie 15 to the end 13. A lug 16 extends downwardly from the rear or abutment end of the bottom flange 6 and has its rear face 17 flush with the abutment end 14 of the body of the shoe. As is best shown in Fig. 1, the top face of the overhanging flange 11 has a groove 18 formed therein, which extends in parallelism with the innermost face of the way 12 in the shoe. It will be noted that the thickness of the material of the shoe is greatly reduced 45 along a line closely adjacent to and outside of the vertical plane extending along the edge 10 of the rail 9.

A yoke of steel or other resilient metal, indicated generally by the reference numeral 19, may be formed of bar stock, square 50 in cross section, and having a hook portion

20 curved complementarily to the body of the shoe 5. The inner face 21 of hook 20 is tapered complementarily to the taper of the body of the shoe. The opposite end 22 60 of yoke 19 is disposed in offset parallelism to the hook portion 20 if desired, the body of the yoke 19 being bent as at 23, to provide such offset relation, and also being bent as at 24 for providing a single point of contact 25 of the yoke 19 with the bottom face 7 of rail 9. It will be understood that the bend 23 may be eliminated if desired. The end 22 of the yoke has an overhanging edge 26, which provides a way 27 for the remaining flange 8 of the rail. The overhanging flange 26 of the yoke is longitudinally grooved at 28, parallel to and adjacent the perpendicular plane of the bottom of the way 27. From the foregoing, it will be 75 noted that the yoke is thus materially weakened closely adjacent the edge 10 of the rail base.

In mounting the device on a rail, the shoe 5 is placed in the position as shown in Fig. 80 1, so that the flange 8 of the rail is snugly embraced in the way 12 of the shoe. The abutment faces 14 and 17 of the shoe and lug are moved into abutment with a perpendicular face 29 of a cross tie 15, after 85 which the yoke is mounted upon the rail by entering the opposite rail flange 8 in the way 27 and then moving the yoke along the rail until the tapered inner face 21 on the hook 20 of the yoke binds upon the outer tapered 90 face of the body 5 of the shoe.

The creeping tendency of the rail serves to wedge the parts so that such creeping tendency is opposed by the cross ties.

It will be noted that in the structure just 95 described, the anchor structure is weakened along the lines 18 and 28, which extend parallel to and just without the edges 10 of the base of the rail 9. It will be further noted that the yoke 19, while exercising a 100 powerful clamping and wedging action, offers no support beneath the weakened portions 18 and 28. From this, it will be clear that when a railroad car wheel, passing along rail 9, becomes derailed, the downward 105 blow or impact of the wheel will be directed to the weakened portion of the anchor or in groove 18 or the groove 28 on the opposite side of the rail. The anchor structure, being materially weakened beneath these 110 grooves, will therefore break under the impact of the derailed car wheel and at the

same time cause the wheel to drop onto the cross tie 15. The advantage of this structure will be apparent when contrasted with the results of derailment when ordinary rail anchors are used. The ordinary rail anchor binds tightly upon the vertical edges of the flanges 8 of the rail and is very sturdy. When a derailed wheel strikes such an anchor, with the force of its great weight behind it, all of said impact is transmitted directly to that portion of the flange 8 which is clamped by such anchor. The result is that the anchor, being stronger than the rail flange, causes notches or half moon fractures 10 in the flanges of the rails. The rails, thus broken by the old type of anchor, are dangerous and unfit for use and must be replaced. The cost of new rails and the labor incident 15 to removing the damaged rail and placing 20 the new one exceeds many times the cost of the anchors.

It is to be understood that the breakable rail anchor may be either of one-piece or two-piece construction and that in either instance, the portions which overhang the flange of the rail base shall be provided with the longitudinal grooves such as 18 and 28 in the device herein described, and that the material of such overhanging portions shall 25 preferably be rounded and sloping toward said grooves so that the impact of a derailed car wheel will strike the anchor either directly in the groove to effect shearing of the anchor or will be effective for breaking 30 the anchor without breaking or notching the rail base.

The invention, therefore, is not limited to the exact structural details hereinbefore set forth, as such structure may be modified in 40 various ways within the scope of the present invention and the appended claims.

What is claimed is:

1. In a breakable rail anchor, the combination of an anchor member adapted to grip 45 opposed longitudinal edges of a rail and to abut a supporting cross tie for said rail, the anchor being grooved longitudinally above the longitudinal edges of the rail for providing weakened portions at which the 50 anchor will break under the impact of a derailed wheel.

2. As a new article of manufacture, a rail anchor adapted to preclude creeping of a rail and having a weakened portion disposed 55 above and slightly without the plane of a vertical edge of a rail base.

3. In a device of the class described, the combination of a shoe member adapted to embrace and overhang a longitudinal edge of 60 a rail base, and having a groove in the top face thereof disposed slightly without the plane of the vertical body line of the longi-

tudinal edge of the rail, and a yoke adapted to hook over the shoe and pass beneath the bottom of the rail and provided with a way 65 for receiving the opposed longitudinal edge of the base of said rail, the body of said yoke adjacent the bottom of the way being grooved whereby to weaken one end of the yoke.

4. In a device of the class described, the combination with a rail having a base flange and a cross tie for supporting said rail, of a shoe having a way therein for receiving one longitudinal edge of the rail base and a yoke adapted to frictionally bind the opposed longitudinal edge of the rail base and said shoe, the shoe and yoke being grooved 70 in their upper faces in parallelism with the longitudinal edges of the rail whereby the yoke and shoe may be broken on either side of the rail under the impact of a derailed car wheel.

5. In a device of the class described, the combination of a shoe having a way there- 85 in for receiving the longitudinal edge of a rail, a tapered body portion on said shoe having a longitudinal groove in the top face thereof, a yoke member having a way in one end thereof for receiving the edge of a rail 90 base opposite the shoe, said yoke being curved upwardly and sidewardly to provide contact centrally of the bottom face of the rail and having a hook portion adapted to frictionally bind the shoe and yoke upon 95 the rail.

6. As a new article of manufacture, a rail anchor having portions adapted to overhang the top faces of a rail base, said overhanging portions being grooved in parallelism with the longitudinal edges of said rail for providing weakened portions adapt- 100 ed to break under the impact of a car wheel.

7. As a new article of manufacture, a rail anchor having a portion adapted to overhang the top face of a rail base, said anchor being weakened to insure breakage of the 105 anchor and separation thereof from the rail when subjected to abnormal downwardly directed impact.

8. As a new article of manufacture a rail anchor having a body adapted to extend transversely beneath a rail base and means connected with each end of the body for frictional binding upon said rail base whereby to resist creeping of the rail, said binding means being adapted for ready separation from the rail base under the downward impact of a derailed wheel to avoid breakage 115 to the rail base.

In testimony whereof, I have hereunto subscribed my name this 3rd day of March, 1927.

JEROME P. COSTELLO.
